UNITED STATES PATENT OFFICE.

JULIUS C. DICKEY, OF SARATOGA SPRINGS, NEW YORK.

MACHINERY FOR CRUSHING QUARTZ, &c.

Specification of Letters Patent No. 28,163, dated May 8, 1860.

To all whom it may concern:

Be it known that I, JULIUS C. DICKEY, of Saratoga Springs, in the county of Saratoga and State of New York, have invented a new and Improved Mode of Constructing Machines for Obtaining Gold from Quartz Rock and Earth; and I do hereby declare that the following is a full and exact description thereof, reference being had to the accompanying drawings and to the letters of reference marked thereon.

The nature of my invention consists in the employment of a hollow revolving cone on a stationary cone made to project above the stationary cone sufficient to form a mortar on the top of the said stationary cone, in combination with stampers—or their equivalents—secured in, and working in the said mortar for the purpose of crushing, grinding and pulverizing quartz rock containing gold. Second, making one or more channels on the base of a stationary cone—or its equivalent—in combination with a hollow revolving cone—or its equivalent—and making on the base and under side of the said revolving cone projections to work in and on the side of one or more channels, on the base of said stationary cone for the purpose of grinding and pulverizing quartz rock and earth containing gold, and forcing the said pulverized rock and earth into the bottom of the said channels in contact with quick-silver, so that the gold can be secured; and also for the purpose of thoroughly working quartz rock and earth so as to secure all the gold. Third, the combination of stampers—or their equivalents—working in a mortar made by a hollow revolving cone projecting above the top of a stationary cone with the pulverizing surfaces made by the said cones coming in contact with each other, and projections made on the under side of the said revolving cone working in, and on the side of one or more channels on the base of the said stationary cone, for the purpose of crushing, grinding and pulverizing quartz rock and earth containing gold.

Figure 1 shows a perspective view, and Fig. 2 a cross section.

50 In Fig. A shows the stationary cone, *b* the revolving cone, *c* the stamper, and *s* the stamper frame.

Similar letters and figures in Fig. 1 refer to like parts.

55 My additional improvements in quartz

crushers, &c., consists in making on the under side of the revolving cone circular projections to work in and on the sides of one or more channels made on the base of the stationary cone. These projections produce an important result, and are three fold in their effect. First, they agitate the quartz and earth mixed with water in the channels, which agitation has a tendency to separate the gold from earth, sulfur, &c., so that the gold can be amalgamated and secured. It is designed to make projections on the projections with the view of a more thorough agitation of the quartz, &c., and to make one or more projections very thin so that they will assist in amalgamation; and to use projections in one or more channels where balls are not used. Second, these projections have also a tendency to pulverize and grind the quartz as it passes out of channel No. 1 into channel No. 2 between the side of the channel and the said projection, as shown by the dotted lines. This result of the projection is a very important one, as it secures the perfect pulverization of the quartz.

The sides of the channels and projections where they come in contact with each other may be made partly or in whole with a grinding surface. The said projections are made to press or grind on the sides of the channels by means of the set screws *c*, which set screws also adjust the revolving cone so as to press or grind on the stationary cone. The said projections have also a third and very important result; which result is to force the pulverized rock and earth containing gold into the bottoms of the channels in contact with quick-silver, so that the gold can be amalgamated and secured; and no quartz, &c., can pass out of one channel into another without being forced into the bottoms of the said channels in contact with the quick-silver.

It is well known that much gold in small particles is lost by its passing off in water before it is brought in contact with quick-silver; and it is partly with the view of saving these small particles of gold that the said projections are made to force the gold in contact with quick-silver; and if pulverized rock and water bearing gold are allowed to run into the mortar it—the gold—will as a matter of course, before it passes through the machine be brought in contact with the quick-silver and be amalgamated. These

105

110

- projections extend down to or—nearly so—
to the bottoms of the channels, and in some
cases it is designed to make them to extend
across the channel at short distance above
5 the quick-silver, and up the opposite side of
the channel and over into an other channel,
and so as to partly, or nearly fill up the
channels all round the cone with an ad-
justable door, or opening with a hinge to
10 it made in or secured to the flange of the
revolving cone between channel No. 1 and
channel No. 3 so that the gold can be re-
moved from the channels when desirable.
These projections produce the same effect—
15 but to a much greater degree—that the
round balls do which were referred to in
my patent granted May 8th 1860.
I make the stationary and revolving cones
of such form and size as will be best adapt-
20 ed to the purposes for which they are in-
tended. On the base of the stationary cone
as shown at Figs. 1, 2 and 3 I make circular
channels. Channels Nos. 1 and 2 are fur-
nished with quick-silver; and as the pulver-
25 ized rock or earth passes down from the
mortar between the cones as shown by the
dotted lines it—the pulverized rock and
earth—is forced into the bottom of channel
No. 1 by the revolving cone *b* and in contact
30 with the quick-silver so that the gold can be
secured. When the pulverized rock, water,
&c., in channel No. 1 rises up to the top of
the projection which separates it—channel
No. 1—from channel No. 2 it passes over into
35 channel No. 2 between the grinding or pul-
verizing surfaces—as shown by the dotted
lines—made by the projection on the revolv-
ing cone working against the side of chan-
nel No. 2. The balls *o o* secured under the
40 revolving cone and working in channels Nos.
1 and 2 are for the purpose of more finely
pulverizing the rock, &c., and bringing the
gold in contact with the quick-silver.
I contemplate in some cases making the
45 channels wider and employing two or more
balls under the revolving cone in one or more
channels, in a line with each other, with a
slight projection between the balls to keep
the quick-silver in a proper position. Quartz
50 rock and earth containing gold can be pul-
verized and worked as much as may be nec-
essary to secure all the gold by increasing
the number of the channels, as the gold that
is not secured in the first channel will be se-
55 cured in one or more succeeding channels.
Channel No. 3 in which the ball *n* is lo-
cated is raised higher up on the stationary
cone than the other channels, and the weight
of the revolving cone *b* rests upon the balls
60 in this channel. This channel is furnished
with oil so that motion may be given to the
revolving cone with less power. In a re-
cess in the revolving cone *b* above the ball *n*
the adjustable block *a* is located and is ad-

justed by the set screw *c*. The object of this 65
adjustment is to adjust the revolving cone *b*
so as to fit the stationary cone *A*, at the dotted
lines, and with reference to the hardness
of the rock to be ground, and the kind of
70 earth to be worked in the machine. The
screws or stop cocks *d d* are for the purpose
of letting out the water from channels Nos.
1 and 2 through the openings *m m*.

That part of channel *m* nearest the out-
side the base of the stationary cone is made 75
wider, and to extend higher up for the pur-
pose of making an opening so that the water
&c. can pass out continually—when the ma-
chine is in motion—into the circular inclined
channel *I*. In this inclined channel a pro-
jection *X* is made for the purpose of retaining
80 quick-silver to secure any gold that may
be in the water earth, &c., as it passes out of
the machine and through this channel on to
the ground. I contemplate making circular 85
channels on the outside base of the sta-
tionary cone, and also to make them on the in-
side of channel No. 3, with suitable outlets
and inlets.

The projection *h* on the revolving cone *b* 90
is for the purpose of hitching a horse—when
horse power is used—to give motion to the
revolving cone. When steam power is used
I make cogs on the under side of the revolv-
ing cone as shown at letter *j* to connect with 95
suitable gearing secured to the base of the
stationary cone for the purpose of giving the
revolving cone the desired motion.

I contemplate making the cones with, and 100
without a grinding surface, and with refer-
ence to the kind of material to be operated
upon. The stamper frame *s* I insert in a
recess on the top of the stationary cone, and
I also contemplate making it with a screw
105 thread so as to screw it into the said cone
with a projection on its top reaching over
and on the top of the revolving cone so as to
secure the said revolving cone more firmly
on the said stationary cone. The stamper
110 frame *s*, I make with projections through
which projections the stamper *e* passes and
works in.

On the inside of the revolving cone as
shown at letter *g*, I make cogs to fit the cog
wheel *k*, secured to the stamper *e*. I also 115
make on the inside of the said revolving cone
below the cogs an incline plane, or planes,
which incline plane passes under the cog
wheel—when the revolving cone is in motion—
secured to stamper *e* and gives the 120
said stamper a jumping motion, so that the
said stamper will fall on the rock and crush
it. The revolving cone also gives the
stamper a continuous rotary motion so that
when it does not receive a jumping motion
125 by the action of the incline plane for the
purpose of crushing the quartz rock it is
made to grind and pulverize the rock. I

design to make the bottom or face of the stamper with a grinding surface; also with projections, circular or otherwise; and with reference to the kind of material to be operated upon.

When quartz rock not sufficiently hard to require the use of the stampers is operated upon, and also when clay cement, &c., is worked in the machine I discontinue the use 10 of the stampers, and make the cones with a grinding surface, with the stationary cone extending farther up into the revolving cone.

The object of this invention is to combine in one machine the essential qualities 15 of the stamping machines now in common use, the quartz mill and the Arastar, or Chihan mill, so as to work quartz rock and earth all that may be necessary in order to 20 obtain all the gold at one and the same time.

Operation: When quartz rock of suitable size is thrown into the mortar the action of the stamper crushes and grinds the rock sufficiently fine so that it will fall into and between the grinding or pulverizing surfaces 25 of the cones as shown by the dotted lines, and is forced by the action of the revolving cone into the bottom of channel No. 1, and in contact with the quick-silver so that the 30 gold can be secured—and when the said channel No. 1 becomes full the quartz rock or earth flows over into channel No. 2 between the grinding or pulverizing surfaces as shown by the dotted lines where it is 35 more thoroughly pulverized and again forced in contact with quick-silver in the bottom of channel No. 2—this process of forcing the rock and earth out of one chan-

nel into another is repeated until all the gold is secured.

When it is desirable to remove the gold 40 water is allowed to run into the mortar until the gold is washed from all impurities, when the machine is stopped running and the gold 45 is removed from the channels. This machine may be used to advantage in lead and other mines, and in which case any number 50 of balls may be thrown loosely into the channels between the arms L on the revolving cone b and forced around in the said channels by the said arms, and in which case also the use of the circular inclined channel may be discontinued, if desirable.

I claim—

A stamper, or stampers working in a mortar made on the top of a stationary cone by a hollow revolving cone working on, and projecting above the top of the said stationary cone, with the pulverizing surfaces made by the said cones coming in contact with each other, in combination with the projections l l, made on the base of the said revolving cone working in and on the side of one or more channels made on the base of stationary cone, for the purpose of crushing, grinding and pulverizing quartz rock and earth containing gold, and forcing the said pulverized rock and earth into the bottoms of the said channels in contact with quicksilver for the purpose of securing the 65 gold.
